SELF-CLOSING GATE

Filed Oct. 7, 1947

Fig. 1.

UNITED STATES PATENT OFFICE

2,537,484

SELF-CLOSING GATE

Albert Scheuermann, Sutter, Ill.

Application October 7, 1947, Serial No. 778,315

4 Claims. (Cl. 39—31)

1

This invention relates to horizontally swinging self-closing gates adapted to swing to open position in opposite directions, and has more particular reference to improved means for hanging such a gate so as to cause it to rise when swung open and to automatically gravitate and swing to lowered closed position after being swung open in either direction.

The exact nature of the present invention, as well as specific objects and features thereof, will become apparent from the following description when considered in connection with the accompanying drawing, in which:

Figure 1 is a fragmentary side elevational view, partly broken away, of a gate in closed position and hung by means constructed in accordance with the present invention;

Figure 2 is a fragmentary horizontal section taken on line 2—2 of Figure 1; and

Figure 3 is a fragmentary vertical section taken on line 3—3 of Figure 1.

Referring in detail to the drawing, the gate is hung on a post 5 and includes a frame 6 in which is secured a wire fabric panel 7. A collar 8 is secured on the lower portion of an end member 6a of the gate frame and has an ear 9 which is rotatable and slidable on the vertical pintle 10 of a hinge bracket 11 secured on the lower portion of the post 5.

In accordance with the present invention, a collar 12 is secured on the upper portion of the end member of the gate frame, and this collar has a horizontal arm 13 rigid therewith which projects within said gate frame and has a grooved wheel 14 journaled on its inner end portion. The inner end of arm 13 is supported by a hanger 15 rigid with and depending from the top of the gate frame 6. Rigidly bolted to and extending across the post 5 is a horizontal bar 16 in which is anchored the ends of a substantially semi-circular rod 17 that extends through the gate frame and is concentric with the axis of pintle 10. The opposite half portions 17a and 17b of rod 17 incline to their point of juncture so as to provide a cam track for wheel 14, and this track is rigidly sustained in a generally horizontal position by brace rods 18 and 18b extending between the sides of said track and the ends of bar 16. Rigidly carried by the bar 16 intermediate the ends thereof is a vertical elongated C-shaped rod 19 forming a vertical track for a second grooved wheel 20 journaled between spaced ears 21 that project from collar 12 toward the post 5. The track 19 projects toward the gate, and the wheel 20 is engaged with the inside of this track so as to

2

prevent tilting of the gate away from the post 5 while permitting the gate to have vertical rectilinear and horizontal swinging movements. It will be seen that the horizontal axes of wheels 14 and 20 are respectively disposed parallel with and at a right angle to the plane of the gate.

In operation, the gate may be swung open in either direction from the closed position thereof shown in the drawing. As the gate is swung open, the wheel 14 rides up one side portion of rod 17 so as to cause the gate to rise. At the same time, wheel 20 rides upwardly on and turns about the rod 19, and ear 9 similarly slides upwardly on and turns about the pintle 10. As soon as the opened gate is released, it automatically gravitates and swings to lowered closed position, the wheel 14 riding down the side portion of rod 17 to the juncture of its side portions, the wheel 20 riding downwardly on and turning about the rod 19, and the ear 9 sliding downwardly on and turning about the pintle 10.

From the foregoing description, it is believed that the construction, operation and advantages of the present invention will be readily understood and appreciated by those skilled in the art. The device is simple and durable in construction and has been found to function efficiently in actual practice. Modifications and changes in detail of construction are contemplated, such as fairly fall within the spirit and scope of the invention as claimed.

Having described the invention, what is claimed as new is:

1. In combination with a single gate post and a gate including a frame, a collar secured on the lower portion of an end member of the gate frame and having an ear, a hinge bracket secured on the lower portion of the post and having a vertical pintle, said ear being rotatable and slidable on said pintle, a collar secured on the upper portion of said end member of the gate frame and having a horizontal arm rigid therewith which projects inwardly from said end member within the gate frame, a grooved wheel journaled on the inner end portion of said arm, a horizontal bar rigidly secured intermediate its ends to and extending across the post, a substantially semi-circular rod anchored at its ends in the ends of said bar and extending through the gate frame concentric with the axis of said pintle, said semi-circular rod forming a track on which said grooved wheel is movably disposed, the opposite half portions of said rod inclining to their point of juncture.
2. In combination with a single gate post and

a gate including a frame, a collar secured on the lower portion of an end member of the gate frame and having an ear, a hinge bracket secured on the lower portion of the post and having a vertical pintle, said ear being rotatable and slidable on said pintle, a collar secured on the upper portion of said end member of the gate frame and having a horizontal arm rigid therewith which projects inwardly from said end member within the gate frame, a grooved wheel journaled on the inner end portion of said arm, a horizontal bar rigidly secured intermediate its ends to and extending across the post, a substantially semi-circular rod anchored at its ends in the ends of said bar and extending through the gate frame concentric with the axis of said pintle, said semi-circular rod forming a track on which said grooved wheel is movably disposed, the opposite half portions of said rod inclining to their point of juncture, and a hanger rigid with and depending from the top of the gate frame and connected to the inner end of said arm.

3. The construction defined in claim 1, in combination with a vertical elongated C-shaped rod rigidly carried by said bar intermediate its ends and forming a vertical track, ears projecting from the second mentioned collar towards the post and having a wheel journaled therebetween upon a horizontal axis at right angles to the plane of the gate, said wheel engaging the inside of the last named track for vertical and turning movement along and about the same in coaxial relation to said pintle.

4. In combination with a single gate post and

a gate including a frame, a collar secured on the lower portion of an end member of the gate frame and having an ear, a hinge bracket secured on the lower portion of the post and having a vertical pintle, said ear being rotatable and slidable on said pintle, a collar secured on the upper portion of said end member of the gate frame and having a horizontal arm rigid therewith which projects inwardly from said end member within the gate frame, a grooved wheel journaled on the inner end portion of said arm, a horizontal bar rigidly secured intermediate its ends to and extending across the post, a substantially semi-circular rod anchored at its ends in the ends of said bar and extending through the gate frame concentric with the axis of said pintle, said semi-circular rod forming a track on which said grooved wheel is movably disposed, the opposite half portions of said rod inclining to their point of juncture, and inclined brace rods connecting the side portions of said semi-circular rod with the ends of said horizontal bar.
